UNITED STATES PATENT OFFICE

WILLIAM B. WHITE, OF DES MOINES, IOWA

FLY-PAPER-SUPPORTING DEVICE

Application filed December 3, 1928. Serial No. 323,381.

The object of this invention is to provide a fly paper supporting device of simple, durable and comparatively inexpensive construction.

5 A further object of my invention is to provide means for supporting a sheet of fly paper in position extended above surrounding objects, which I find is a much more effective position for accumulating flies on the fly 10 paper, since they have a tendency to alight on raised objects rather than table tops, store counters, and the like.

More particularly, it is my object to provide a supporting frame with a drum rotatably mounted relative thereto and provided with means by which a sheet of fly paper may be attached to or detached from the drum.

Still a further object is to provide the supporting frame with a trough arranged below 20 the fly paper drum for catching any of the sticky substance of the fly paper which may drop from the paper when positioned on the drum.

With these and other objects in view my 25 invention consists in the construction, arrangement and combination of the various parts of my device, whereby the objects contemplated are attained, as hereinafter more fully set forth, pointed out in my claims and 30 illustrated in the accompanying drawings. Although the invention is susceptible of a variety of embodiments, it is unnecessary to fully describe and illustrate more than one in order to give a full understanding of the 35 invention both from its structural and functional standpoints. Accordingly, I have illustrated a preferred and desirable embodiment of the invention in the accompanying drawings in which:

40 Figure 1 is a perspective view of my improved fly paper supporting device.

Figure 2 is a side elevation of the same, parts being broken away and other parts shown in section for illustrating the construction thereof.

Figure 3 is a detail sectional view on the line 3—3 of Figure 2; and

Figure 4 is an enlarged sectional view on the line 4—4 of Figure 3.

45 On the accompanying drawings I have

used the reference character A to indicate generally, a supporting frame and B, a drum to which a sheet of fly paper may be affixed. The supporting frame A consists of end members 10, side members 12, and a bottom portion 14 spaced above the bottom of the supporting frame. Each end member 10 is provided with an outwardly depressed socket 16 preferably formed in the metal of the end plate 10. The drum B consists of a cylindrical portion 18 and drum heads 20. The drum heads 20 may be soldered or welded in position relative to the cylinder 18 or may be merely forced into position.

Each drum head 20 is provided with a hub 22 having a spindle pin 24 inserted therethrough and held relative thereto by soldering or the like. The spindle pins 24 project from opposite ends of the drum B, as clearly illustrated in Figure 2 of the drawings. The spindle pins 24 are adapted to be received in the sockets 16 of the end plates 10 of the supporting frame A. It will be noted that the sockets 16 are arranged in such a manner as to be open at their upper ends, whereby the drum B may be lifted for removing it from the supporting frame A.

45 A sheet of fly paper 26 may be wrapped around the drum B and may be secured thereto in any desirable manner. On my drawings I have illustrated one end of the sheet 26 as being positioned on sharpened pins 28 extending out of the drum cylinder 18.

The sheet 26 may then be wrapped around the drum B and lapped over the opposite end of the sheet as indicated at 30. The overlapping portion 30 is also pierced by the pins 28 and may be held in position relative to the pins to prevent its accidental removal therefrom by means of spring clips 32. The spring clips 32 may be secured to the drum B in any desired manner and are provided with openings 34 to receive the pointed ends of the pins 28, as best shown in Figure 4.

Practical use of my device

In the use of my device, one end of the fly paper is positioned on the pins 28. The drum is then rotated for winding the paper thereon and the free end of the paper is positioned

on the pins 28. The spring clips 32 may be raised by the fingers of the operator during this operation and after being released, will retain the paper in position. The drum B 5 may be removed from or remain in position on the frame A, as found best suitable for performing the operations of removing one sheet of fly paper and applying another.

In the summer time, when the temperature 10 is high, the sticky substance on the fly paper 26 sometimes has a tendency to melt and run down to the lowermost part of the drum and drip off. To prevent such drippings from 15 falling onto a table or the like, I provide the bottom 14, which together with the upper portions of the end members 10 and the upper portions of the side members 12 form a trough.

Some changes may be made in the construction 20 and arrangement of the parts of my device without departing from the real spirit and purpose of my invention, and it is my intention to cover by my claims, any modified forms of structure or use of mechanical 25 equivalents, which may be reasonably included within their scope.

I claim as my invention:

1. In a fly paper holder, a supporting frame having end members provided with depressions therein, a drum adapted to have a sheet of fly paper affixed thereto, spindles on said drum extending into said depressions, said supporting frame having sides with their ends connected to the side edges of said ends 25 and a partition between the top and bottom of the frame to provide a trough below said drum.
2. In a fly paper holder, a support, a drum mounted thereon, and means for securing a sheet of fly paper around said drum, said means comprising sharpened pins and clips adapted to engage overlapping ends of the fly paper.

Des Moines, Iowa, November 22, 1928.

WILLIAM B. WHITE.
